(57) **CLAIM**

The ornamental design for a digital camera, as shown and described.

DESCRIPTION

FIG. 1 is a front, top and right side perspective view of a digital camera, showing our new design;

FIG. 2 is a front, top and right side perspective view thereof, showing the state in which a barrier is opened and a cover of the electric flash is opened;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines are included for the purpose of illustrating environmental structure only and form no part of the claimed design.
